Primary Examiner — Elizabeth J Oswecki*Assistant Examiner* — Lacey Chey Bowman(74) *Attorney, Agent, or Firm* — Jeenam Park(57) **CLAIM**

The ornamental design for a pipe inspection camera, as shown and described.

DESCRIPTION

FIG. 1 is a front, right and top perspective view of a pipe inspection camera, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged portion view thereof taken from encircled portion labeled, “9,” in FIG. 1.
The dot-dash broken lines form the boundary of the enlarged portion view of FIG. 9 in FIGS. 1 and 9 and form no part of the claimed design. The even dashed broken lines shown in the drawings are included for the purpose of illustrating portions of the pipe inspection camera that form no part of the claimed design.
